(57) **CLAIM**

I claim the ornamental design for a double faced hair barrette, substantially as shown and described.

DESCRIPTION

FIG. 1 is a perspective view of an embodiment of the double faced hair barrette of the present invention;

FIG. 2 is a top plan view of the embodiment of FIG. 1;

FIG. 3 is a bottom plan view of the embodiment of FIG. 1;

FIG. 4 is a first side elevation view of the embodiment of FIG. 1;

FIG. 5 is an opposing second side elevation view of the embodiment of FIG. 1;

FIG. 6 is a front elevation view of the embodiment of FIG. 1; and,

FIG. 7 is a rear elevation view of the embodiment of FIG. 1.
